HAULSEY B. MASTON AND ONE-FOURTH TO GEORGE L. TOWNSEND, JR., BOTH OF
WILMINGTON, DELAWARE.

TRAIN-STOPPING SYSTEM.

1,208,699.

Specification of Letters Patent. Patented Dec. 12, 1916.

Application filed November 18, 1914. Serial No. 872,817.

To all whom it may concern:

Be it known that I, WILLIAM E. TIBBETT, a citizen of the United States, residing in New Castle, county of New Castle, State of Delaware, have invented certain Improvements in Train-Stopping Systems, of which the following is a specification.

One object of my invention is to provide a relatively simple, substantial and reliable combination of apparatus for automatically applying the air brakes of a locomotive or train attempting to run by a signal or equivalent device when this is in the "danger" position; the invention also contemplating the provision of means whereby the engineer may conveniently release the brakes after they have been so set. These objects and other advantageous ends I secure as herein-after set forth, reference being had to the accompanying drawings in which,

Figure 1 is a diagrammatic view illustrating a section of track with signals and certain associated parts arranged in accordance with my invention, Fig. 2 is a diagrammatic view illustrating the apparatus constituting my invention, Fig. 3 is a sectional elevation of one of the ramps or stationary contacts, preferably forming part of my system, and Fig. 4 is a fragmentary diagram illustrating a modification of one feature of the invention.

In the above drawings 1 represents a portion of a railroad track along which are mounted signals of any desired type and at any suitable intervals. In any case, however, each of these signals is made to include a member, such as a semaphore arm 2 or 2^a, movable under conditions of operation into two or more positions, in one of which the signal is set at "danger."

In the present instance I have shown the semaphore arms as mounted on posts or columns 3 and 3^a and each of said arms or movable members carries or includes a metallic piece preferably in the form of a blade 4 constituting a switch arm. In addition the post or other support 3 or 3^a carries two terminal contacts 5 and 6 designed to be electrically connected by the blade or piece 4, at such time as the arm or movable member 2 or 2^a occupies its "danger" position. These two terminal contacts are respectively connected to a pair of contact plates or

ramps 7 and 8 mounted adjacent the rails 9 of the railroad, preferably in the vicinity of 55 the signal post 3, and the connections between one of these terminal contacts and its ramp includes a battery or other source of current 10.

Each locomotive or train operated over 60 the railroad carries or has mounted upon it a pair of brushes or contact shoes 11 and 12 so placed as to respectively contact electrically with the ramps 7 and 8 of each signal when said train arrives at or passes the same, 65 and in order to avoid injury as well as to diminish the shock of engagement, the shoes or brushes are preferably resiliently mounted on their supporting structures the ramps being likewise supported on springs 13, so 70 that they as well as the shoes are free to yield when engaged. Moreover I preferably make the ramps of a body 14 of insulating material beveled downwardly from its center toward its ends and having fixed to its upper convex surface a strip or sheet of metal such as copper. Similarly the contact shoes or brushes are preferably convexly curved so as to engage the strips 15 of their respective ramps with the least possible shock. 80 Also mounted on the locomotive or on one or more cars of the train is a pair of solenoids 16 and 17 having a longitudinally movable core 18 connected to the operating handle or lever 19 of a valve 20. Said valve is connected in a pipe 21 forming a portion of the air brake system and is so disposed relatively to the core 18 that when the latter is drawn into the solenoid 17, said valve is closed, while when the core is drawn into the 90 solenoid 16, said valve is opened, thereby causing setting of the brakes of the system.

One terminal of the solenoid 16 is permanently connected to the brush or shoe 12 while its second terminal is connected to the 95 terminal 22 of a hand switch 23, whose second terminal 24 is permanently connected to the second brush or shoe 11. One terminal of the solenoid 17 is likewise connected to the terminal 22 of the switch 23 and its second terminal to a third terminal 25 of the switch 23 through a source of current 26 such as a battery. The movable member of said switch is preferably placed or is equipped with a spring 27, so as to at all 105 times tend to connect the terminals 22 and

24, although it may be moved against the action of this spring into temporary engagement with the terminal 25.

Under normal conditions of operation the engineer or motorman sets the apparatus by momentarily moving the blade of the switch 23 into engagement with the contact 25, thereby energizing the solenoid 17 and causing it to close the valve 20 through the handle or lever 19. Thereafter said switch member is moved or permitted to move into engagement with the terminal 24, and obviously as the locomotive or car carrying the above described apparatus moves over the ramps 7 and 8 of any signal, the brushes 11 and 12 respectively contact with the latter. As long as the movable member 2 or 2^a of the signal with which said ramps are associated, occupies a safety or caution position, the circuit through the solenoid 16 remains open.

When the movable member of the signal occupies the "danger" position, as in the case of the member 2, the blade 4 closes or 25 completes the circuit between the terminal contacts 5 and 6, and when the ramps 7 and 8 of said signal are engaged by the shoes or brushes 11 or 12, current flows from the source 10, through the terminal 5, blade 4 and terminal 6 to the ramp 8, brush 12, solenoid 16, switch 23, brush 11 and ramp 7 back to said source. As a result, said solenoid is energized and draws the core 18 away from the solenoid 17, into such position as to cause opening of the valve 20, with a consequent setting of the air brakes. The locomotive or train is thus stopped, thereby calling attention to the danger position of the signal, though if the engineer desires to 30 operate his train beyond said signal, he merely opens the switch 23 until the train passes the signal or the ramps connected therewith.

Obviously, without departing from my invention, the valve 20 may be so adjusted as to be opened in order to cause release of the air brakes when it is desired to run the engine or car past the signal in the "danger" position, since the specific construction of 45 said valve will depend upon the system of brakes with which it is used. In some cases the pipe 21, instead of being connected in the air-brake system, may form part of an alarm system so that the opening or closing of the 50 valve 20 will operate a suitable form of alarm. Preferably however, the arrangement is such that the locomotive or train is automatically brought to rest whenever it is attempted to run it past a signal occupying 55 the "danger" position.

For the sake of clearness I have referred to the switch 5-4-6 with the source of current 10 and the contacts 7 and 8 as a track circuit and it is obvious that if desired one 60 of said contacts with its coacting brush may

be omitted merely by grounding one of the terminals of said track circuit as well as the corresponding terminal of the train circuit. In the present instance this latter consists of the electro-magnet 16, the switch 24-23-22, 75 and one or both of the contacts 11 and 12 as the case may be.

It will be understood that it is by no means necessary that the switch 5-4-6 should be directly closed by movement of the semaphore arm, since, without departing from my invention, it may be arranged in any suitable manner so that it is caused to close when the signal or equivalent mechanism occupies a "danger" position. Furthermore, while I have shown a source of current 10 connected in each of the track circuits and another source of current 26 connected in the re-setting circuit which includes the electro-magnet 17, I may if desired or advisable, employ a single current source 31 connected as shown in Fig. 4 between the terminal 22 of the hand switch and the conductor 30 which is connected to one terminal of each of the magnets 16 80 and 17.

One particularly valuable feature of my invention resides in the fact that a train standing on the near side of the signal 3 for example, is protected by the signal 3^a even 95 though said first signal is in the safety position, since obviously said second signal would be in the "danger" position and would automatically cause stopping of a following train, whose brushes 11 and 12 come into 100 contact with the ramps 7 and 8.

I claim;—

1. The combination of train stopping means; two electro-magnets for operating said means; a source of current; means for 105 causing at will the energization of one of said magnets; and automatically acting signal-controlled means for controlling the energization of the other magnet and the consequent operation of the train stopping device. 110

2. The combination of a train stopping device; two electro-magnets for controlling said device; a current source; a double throw switch connected to cause energization of one of said magnets when in one position and to complete a portion of the circuit of the other magnet when in a second position; a track circuit having means for completing the circuit of the second magnet; and signal controlled means in said circuit for permitting flow of current under predetermined conditions. 115 120

3. The combination of a signal; a switch mounted to be closed when said signal occupies a "danger" position; a track contact in circuit with said switch; a source of current; a train circuit including a brush placed to engage said contact; an electro-magnet in circuit with said brush; a train controlling 125 130

valve operatively connected to the movable member of said magnet; a second electro-magnet also operatively connected to the valve; and means for causing energization of said second magnet at will.

4. The combination of a railroad track; a series of signals spaced at predetermined distances apart along said track; a track circuit for each signal including a source of current, at least one contact mounted adjacent the track, and a switch mounted to be closed when said signal occupies a "danger" position; with apparatus carried by each of the trains operating on the track, the same including a valve connected in the air brake

system, two electro-magnets having their movable elements operatively connected to said valve, at least one brush in circuit with one of the magnets and mounted to coöperate with the contacts of the track circuits; and means for causing energization of the second magnet at will. 2c

In testimony whereof, I have signed my name to this specification, in the presence of two subscribing witnesses.

WILLIAM E. TIBBITT.
